FIG. 1

FIG. 2

FIG. 7

FIG. 3

FIG. 4

FIG. 5

FIG. 6

Fig. 1 is a top plan view of the airplane showing our new design in one flight condition, with the propeller cowling flaps in closed position;

Fig. 2 is a front elevational view of the airplane of Fig. 1;

Fig. 3 is a side elevational view thereof;

Fig. 4 is a top plan view of the airplane in another flight condition, with the cowling flaps opened;

Fig. 5 is a front elevational view of the airplane of Fig. 4; and

Fig. 6 is a side elevational view thereof;

Fig. 7 is an enlarged scale fragmentary top-rear perspective view.

The airplane is symmetrical; the opposite side being essentially like the side shown in the drawing.

We claim:

The ornamental design for an airplane, as shown and described.
